UNITED STATES PATENT OFFICE.

MARTINIUS DYSTHE, OF CROOKSTON, MINNESOTA.

DRAWER AUTOMATIC COVER PLACER.

Application filed December 12, 1921. Serial No. 521,697.

To all whom it may concern:

Be it known that I, MARTINIUS DYSTHE, a citizen of the Dominion of Canada, residing at Crookston, in the county of Peck and State of Minnesota, have invented certain new and useful Improvements in Drawer Automatic Cover Placers; and I do hereby declare the following to be a full, clear, and exact description of the invention, such as will enable others skilled in the art to which it appertains to make and use the same.

This invention relates to a cover structure for drawers and is particularly designed for the bread drawer of a kitchen cabinet or for stores where it is desired to keep various articles in the drawer which require that the drawer be covered.

It is an object of this invention to provide a sliding drawer of the usual type with a cover which is slidably mounted in the drawer and has limited movement therewith.

It is a further object of the invention to have the cover connected to the frame in which the drawer is mounted by a flexible means which limits the sliding movement of the cover with the drawer.

These and other objects and advantages of the invention will be apparent from the following description made in connection with the accompanying drawings in which like reference characters refer to the same parts throughout the different views and in which—

Fig. 1 is a view in vertical section through a frame and drawer showing the invention applied thereto;

Fig. 2 is a horizontal section taken on line 2—2 of Fig. 1; and

Fig. 3 is a vertical section of one side of the drawer taken on line 3—3 of Fig. 1.

Referring to the drawings, a cabinet or other frame a is illustrated, said frame having the front cross piece a^1 and a drawer 2 is slidably mounted in this frame, the front portion of which projects forwardly and abuts against the front of the member a^1 when the drawer is in closed position. The drawer 2 has a cover member 3, slidably mounted in slots formed on the inside of the drawer sides and this cover abuts at its front end against the front end of the drawer 2 when the drawer is in closed position. The cover 3 is arranged to be connected to the frame a and for this purpose a transversely extending ear 3^a is struck up from the cover 3 substantially centrally of the width there-

of and a connecting member or bar 4 is held in this ear. The member 4 comprises a rod bent into U-shape, one leg of the U passing through or beneath the ear 3 and the other leg passing at the top or outside thereof, this latter leg being bent to provide an eye substantially centrally of its length and having its free end bent into a loop or hook disposed at substantially a right angle to its length which loop passes around and engages the end of the other leg whereby the member is securely engaged with and locked to the ear 3. A hook bolt or lag screw 5 is screwed into the inner side of the frame member a^1 and projects with its inner hooked end disposed substantially over the center of the drawer 2 and cover 3 and the hook end of this bolt is connected by a flexible member comprising a chain 6 to the eye in member 4. The cover 3 is thus movably and flexibly connected to the frame a .

Normally, with the drawer in closed position as shown in Fig. 1, the chain 6 will be inclined rearwardly of the drawer, the cover being moved to its inward position by engaging with the front of the drawer. When the drawer is withdrawn, as shown in dotted lines in Fig. 1, the cover 3 will move part way therewith but this movement will be limited by the chain 6 so that when the drawer is moved to open position, the chain will occupy the position shown in dotted lines in Fig. 1 at which time the cover will project slightly in front of the frame. With this structure, the rear portion of the drawer is always covered and only enough of the front portion thereof will be uncovered to enable the desired article to be withdrawn therefrom. The articles in the drawer are therefore largely protected from dust and dirt. The length of the flexible member 6 can, of course, be varied to provide the amount of opening desired.

From the above description, it is seen that applicant has provided a simple and efficient structure of drawer cover and one having great utility. The parts can be provided at small expense and are so simple that no attention will be required to keep them in working order. Said parts are also arranged for easy removal in case it is desired to wholly withdraw the drawer.

It will, of course, be understood that various changes may be made in the form, details and proportions of the parts without departing from the scope of applicant's in-

vention which, generally stated, consists in the matter shown and described and set forth in the following claims.

What is claimed is:

- 5 1. In combination with a frame and a drawer slidably mounted therein, a cover slidably mounted in the side of said drawer and flexible means pivotally connected to said cover and said frame for limiting the movement of said cover.
- 10 2. The structure set forth in claim 1, said cover being adapted to abut the front of said drawer when the latter is in closed position.
- 15 3. In combination with a frame and a drawer slidably mounted therein, a cover comprising a plate slidably mounted in the side of said drawer, a member secured in the frame and projecting over said cover, flexible means secured to said member and to said cover whereby sliding movement of the cover with the drawer will be limited.
- 20 4. In combination with the frame and a drawer slidably mounted therein, a cover for said drawer slidably mounted in the sides thereof, a hook secured in the frame and disposed with its end located substantially over the center of said drawer, a flexible member connected to the end of said hook and connected at its other end to said cover substantially at the center thereof.
- 25 5. In combination with the frame and a drawer slidably mounted therein, a cover

slidably mounted in said drawer having an ear projecting upwardly therefrom substantially centrally transversely thereof, a connecting member detachably connected to said ear and having a central connecting eye thereon, a hook secured in said frame and projecting over said cover in longitudinal alignment with said eye and a chain connected to said hook and to said eye whereby sliding movement of said cover with the drawer will be limited.

40 6. The combination with a frame and a drawer slidably mounted therein, a cover slidably mounted over the drawer, and a flexible means disposed above said cover and connected to the frame and to the top of the cover intermediate the length thereof for 45 limiting the opening movement of said cover.

50 7. The combination with a frame and a drawer slidably mounted therein, of a cover slidably mounted over said drawer, a hook member screwed into the frame and extending rearwardly over the cover, a chain having one end engaged in said hook, a connecting member extending transversely of said cover and attached thereto having an 55 upstanding loop in which the other end of said chain is connected.

In testimony whereof I affix my signature.

MARTINIUS DYSTHE.
